[57] CLAIM

The ornamental design for a heel stabilizer, as shown and described.

DESCRIPTION

FIG. 1 is a left side elevational view of a heel stabilizer showing my new design, the right side being a mirror image thereto;

FIG. 2 is a top plan view thereof;

FIG. 3 is a bottom plan view thereof;

FIG. 4 is a front elevational view thereof;

FIG. 5 is a rear elevational view thereof;

FIG. 6 is a cross-sectional view as taken from line 6—6 of FIG. 1;

FIG. 7 is a cross-sectional view as taken from line 7—7 of FIG. 2.

The left side elevational view is identical to the right side elevational view.
